UNITED STATES PATENT OFFICE.

MARGARET E. BURNS, OF CHICAGO, ILLINOIS.

HEAD ATTACHMENT.

1,169,123.

Specification of Letters Patent. Patented Jan. 25, 1916.

Application filed March 17, 1915. Serial No. 14,964.

To all whom it may concern:

Be it known that I, MARGARET E. BURNS, a citizen of the United States, and a resident of the city of Chicago, county of Cook, and 5 State of Illinois, have invented certain new and useful Head Attachments, of which the following is a specification.

My invention relates to a certain new and useful head attachment adapted for use in 10 treating and caring for persons suffering from headache, the object of the invention being to provide a simple and efficient attachment of this character which may be readily applied and which will give relief. 15 The invention consists in the combinations and arrangements of parts hereinafter described and claimed.

The invention will be best understood by reference to the accompanying drawing 20 forming a part of this specification, and in which,

Figure 1 is a view of an attachment embodying my invention and shown in position of use, Fig. 2, a perspective view of a head 25 band employed in the construction, shown detached and with portions broken away for the sake of clearness, Fig. 3, an enlarged section taken substantially on line 3—3 of Fig. 2, Fig. 4, an enlarged section taken on substantially line 4—4 of Fig. 2, and Fig. 5, an 30 enlarged sectional view illustrating the method of attaching a head cap, employed in the construction, to the head band.

The preferred form of construction, as 35 illustrated in the drawing comprises an annular head band 6 made of cloth or other suitable flexible material and in the form of a channel member open at its top. A plurality of flexible hot water bottles 7 are arranged in band 6, said bottles being positioned, as indicated, so as to bring one of them directly over the forehead of the wearer and one at each side of the forehead, as indicated. These hot water bottles are substantially 45 triangular in form and are provided with filling tubes 8 closable by means of clamps 9, as indicated, said hot water bottles being normally held in position in the head band 6 by means of strings 10 which 50 are tied together to fasten the adjacent edges of band 6 together and thus hold the water bottles in place due to their triangular shape. Draw strings 11 are also arranged at the rear of the band 6 at the top and bottom 55 thereof to serve as a means for adjusting the

length of the band to the head of the wearer, as will be readily understood.

A head cap 12 is detachably secured to the upper portion of head band 6 by means of strings 13 which are knotted, as shown, to effect such securing. An ordinary ice container 14 is arranged in the head cap 12 so that ice may be applied to the top of the head of the wearer when desired.

While I have illustrated and described 65 the preferred form of construction for carrying my invention into effect, this is capable of variation and modification without departing from the spirit of the invention. I, therefore, do not wish to be limited to the 70 precise details of construction set forth, but desire to avail myself of such variations and modifications as come within the scope of the appended claims.

Having described my invention what 75 I claim as new and desire to secure by Letters Patent is:

1. A device of the class described comprising a band adapted to encircle the head; a hot water container detachably mounted 80 on said band; a cap detachably connected with said band; and an ice container in said cap, substantially as described.

2. A device of the class described comprising a band adapted to encircle the head; 85 a plurality of hot water containers detachably mounted on said band; a cap detachably connected with said band; and an ice container in said cap, substantially as described.

3. A device of the class described comprising a band in the form of a channel adapted to encircle the head; and a hot water container detachably mounted in said channel, substantially as described.

4. A device of the class described comprising a band in the form of a channel adapted to encircle the head; a hot water container detachably mounted on said band; a cap detachably connected with said band; and an ice container in said cap, substantially as described.

5. A device of the class described comprising a band in the form of a channel adapted to encircle the head; a plurality of hot water containers detachably mounted in said channel; a cap detachably connected with said band; and an ice container in said cap, substantially as described.

6. A device of the class described com-

prising a band in the form of a channel adapted to encircle the head; a plurality of hot water containers removably mounted in said channel; a cap detachably connected with said band; an ice container in said cap; and means for adjusting the length of said band, substantially as described.

In testimony whereof I have signed my name to this specification in the presence of two subscribing witnesses.

MARGARET E. BURNS.
